US00D952013S

(12) **United States Design Patent** (10) **Patent No.:** **US D952,013 S**
(45) **Date of Patent:** **** May 17, 2022**

(54) **DUAL CAMERA**

(71) Applicant: **GETAC TECHNOLOGY CORPORATION**, Hsinchu County (TW)

(72) Inventor: **Chun-Hsing Li**, Taipei (TW)

(73) Assignee: **GETAC TECHNOLOGY CORPORATION**, Hsinchu County (TW)

(**) Term: **15 Years**

(21) Appl. No.: **29/725,597**

(22) Filed: **Feb. 26, 2020**

(51) **LOC (13) Cl.** **16-01**

(52) **U.S. Cl.**

USPC **D16/200**; D16/203

(58) **Field of Classification Search**

USPC D16/200–204, 205–211

CPC G03B 15/03; G03B 15/05; G03B 17/02; G03B 17/56; G03B 2219/02; H04N 5/2251; H04N 5/2252; H04N 5/2253; H04N 5/2254; H04N 5/2255; H04N 5/232939; H04N 2101/00

Assistant Examiner — Lacey Chey Bowman

(57) **CLAIM**

The ornamental design for a dual camera, as shown and described.

DESCRIPTION

FIG. 1 is a top, front, and right side perspective view of a dual camera, showing my new design;

FIG. 2 is a top, rear, and left side perspective view thereof;

FIG. 3 is a bottom, rear, and left side perspective view thereof;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a top, front, and right side perspective view thereof showing one of cameras being rotated relative to the other;

FIG. 11 is a top, rear, and left side perspective view thereof showing one of cameras being rotated relative to the other; and,

FIG. 12 is a bottom, rear, and left side perspective view thereof showing one of cameras being rotated relative to the other.

(Continued)

The broken lines in the figures illustrate the portions of the dual camera that form no part of the claimed design.

1 Claim, 12 Drawing Sheets
